UNITED STATES PATENT OFFICE.

JAMES JOHN HEWSON, OF MACLEOD, CANADA, ASSIGNOR OF ONE-HALF TO
WILLIAM FRANCIS COCHRANE, OF MACLEOD, CANADA.

SINGLE-TRIGGER MECHANISM.

SPECIFICATION forming part of Letters Patent No. 722,706, dated March 17, 1903.

Application filed October 9, 1901. Serial No. 78,080. (No model.)

To all whom it may concern:

Be it known that I, JAMES JOHN HEWSON, a subject of His Majesty the King of Great Britain, residing at Macleod, Alberta, North-West Territories, Canada, have invented certain new and useful Improvements in Single-Trigger Mechanism for Double-Barreled Firearms; and I do hereby declare that the following is a full, clear, and exact description of the invention, such as will enable others skilled in the art to which it appertains to make and use the same.

My invention relates to a single-trigger mechanism for double-barreled guns—as, for example, for breech-loading shotguns of that class in which the barrels break downward in order to open the gun for loading and to simultaneously cock the hammers of the locks for the right and left hand barrels—although the principle of this invention may be availed of in the construction of other types of guns.

One object that I have in view in the present invention is the provision of a simple, efficient, and thoroughly practical single-trigger mechanism in which the discharge of one barrel is followed by the automatic operation of the parts of the trigger mechanism in a manner to place the same in condition for firing the second barrel, so that when an intentional second pull on the trigger is made by the shooter said second barrel will be discharged, whereby the two barrels may be discharged by simply exerting the necessary number of pulls on one and the same trigger and the discharge of the second barrel may take place, not necessarily and immediately following that of the first barrel, but at any desired interval and at the pleasure or will of the marksman.

A further object of the invention is the provision of recoil-actuated locking mechanism in operative relation to the single-trigger mechanism, designed and intended to automatically and effectively prevent the unintentional discharge of the second barrel immediately following the firing of the cartridge in the first barrel, which accidental discharge of said second barrel is due under some circumstances to the recoil of the gun immediately following the discharge of the first barrel, causing the marksman to pull the trigger

a second time without his ever being conscious of such a second pull on the trigger.

One feature of the invention is a recoil-actuated mechanism occupying an operative relation to the single-trigger mechanism and adapted to prevent the trigger from moving far enough toward its normal position to allow the sear-actuator to move into position for firing the second barrel during the period of recoil of the gun.

The invention further consists in the novel combinations of mechanisms and in the construction and arrangement of parts, which will be hereinafter fully described and claimed.

In order that others skilled in the art may fully understand my invention in its relation to the standard makes of breech-loading guns, I have illustrated different embodiments of said invention in connection with different types of guns by the accompanying drawings, forming a part of this specification, and in which—

Figure 1 is a vertical longitudinal section of certain parts of the gun known as a "Baker" gun and representing the single-trigger mechanism in position for firing the right-hand barrel. Fig. 2 is a skeleton plan view of the single-trigger mechanism occupying its normal operative relation to the right and left locks of the gun shown by Fig. 1. Fig. 3 is a view in side elevation, showing the parts of the right lock after the first barrel shall have been discharged and with the single trigger in position for actuating the left lock in order to discharge the second barrel. Fig. 4 is a detail perspective view of the right lock removed from the gun and representing the sear-tail which forms the operative connection between the single trigger and the sear for the hammer of the right lock. Fig. 5 is a detached perspective view of the trigger. Fig. 6 is a like view of the trigger-plate. Fig. 7 is a similar view of the actuator. Fig. 8 is a like view of the recoil-actuated locking device. Fig. 9 is a similar view of the slideable setting-piece adapted to be actuated on the cocking of the gun and to place the actuator in position for engagement with the sear of one lock. Fig. 10 is a detail view of a spring adapted to actuate both the trigger

and the actuator. Figs. 11 and 12 are details of a cocking-lever of the type used in the Baker gun. Figs. 13 and 14 are detail views of parts associated with a Baker gun adapted 5 to secure the certain action of the recoil-detent.

The same numerals of reference denote like parts in each of the several figures of the drawings.

10 The breech of the gun is indicated by the numeral 5, the forward part of the body or frame by the numeral 6, the barrel-locking lever by the numeral 7, and the hammer-cocking lever by the numeral 8. Said hammer-cocking lever is shown in detail by Figs. 11 and 12, and the upstanding arm of this lever is provided with the laterally-extending arms 9, 9^a, which are arranged to have engagement simultaneously with the hammers of the right 15 and left hand gun-locks, said gun-locks being indicated by the numerals 10 and 11 in Fig. 2. The right-hand gun-lock is shown detached by Fig. 4 and is also shown by Figs. 1 to 3, inclusive, and by reference to these figures it 20 will be seen that each gun-lock is similar to devices ordinary in the art, except that the sears are provided with peculiar constructions of tails.

As a full and clear understanding of the 25 lock is desirable, reference will be made to Figs. 3 and 4, in which the lock-plate is indicated by the numeral 12, and the hammer 13 is pivoted at 13^a to the lock-plate and is provided with the bent 14. The mainspring 15 is arranged to engage with the flat under face 16 of the hammer and is seated upon a projection 17 of the lock-plate, and the sear 18 is provided with an upstanding ear 19, that is pivoted at 20 to the lock-plate, said sear and 30 the upper member of the mainspring 15 being arranged in such relation to each other that said spring member will engage with the under face of the sear when the hammer is thrown to the position shown by Fig. 3 in order 35 to impel the firing-pin, whereby the sear will be held in its raised position by the energy of the spring. The sear 18 for the right-hand gun-lock is provided with a sear-tail 21, that extends from the lock inwardly toward the 40 median line of the gun, so that it may have proper engagement with the sear-actuator to be hereinafter described, and the sear 18 for the left-hand gun-lock 11 has a tail 22, which, as shown by Fig. 2, also extends inwardly 45 from the lock toward the median line of the gun, as will be readily understood by reference to the drawings. From this description, taken in connection with the previous description, it will be understood that the sear-tails 21, 22 of the sears of the two gun-locks extend in opposite directions from the lock and inwardly toward each other, and assuming that the normal positions of the gun-locks is when both of the hammers 13 shall have 50 been cocked by the action of the arms on the cocking-lever 8 the two sear-tails 21, 22 of the gun-locks will lie substantially in alinement

with each other, as shown by Fig. 2, and in position so that the right-hand sear 21 will be in engagement with the sear-actuator, while 70 the sear-tail 22 for the left-hand lock will occupy a position in the path of the sear-actuator which will enable the latter to engage with said sear-tail 22 after the cartridge in the first or right-hand barrel shall have been discharged by the action of the hammer of the right-hand lock upon the firing-pin associated with said barrel when the trigger is purposely pulled a second time after being released subsequent to the first discharge. 80

In the construction of the gun-lock hereinbefore described the sear-tail for the right lock may be provided with a straight rear face 23, and it may also be provided with a curved front face 24, and the sear-tail of the right-hand lock is arranged in the normal position of the parts when the gun is loaded to engage with a notched upper end of the sear-actuator, as will hereinafter appear and as shown more particularly by Fig. 1. 90

25 designates the trigger-plate, which is adapted to be secured to the stock in any usual or preferred way, said plate being provided with the trigger-guard 26, that is disposed below the outside of the gun. The 95 trigger-plate is provided with an upstanding standard 27, the latter being made fast with the trigger-plate at a point intermediate of its length and said standard having a horizontal slot 28, formed therethrough below the solid upper end or head of the standard. Furthermore, the trigger-plate is provided with a trigger-slot 29, and adjacent to this slot said trigger-plate is provided with the lugs 30, the latter adapted to support the recoil-actuated detent, to be hereinafter described. 100

The trigger 31 is shown in detail by Fig. 5 and in its assembled position by Fig. 1. This trigger consists of a finger-piece 32 and the 110 parallel plates 33, 34, the latter being integral with the finger-piece and arranged in such relation one to the other as to form an intermediate slot 35. The parallel plates of the trigger have the notches 36 in the upper front 115 corners thereof. Said plates are arranged with the upstanding ears 37 and with the rearwardly-extending lugs 38, the latter having the undercut inclined edges 39. (See Fig. 5.) The trigger is arranged in such relation to the trigger-plate 25 that the finger-piece may extend into the guard, while the lower portion of the trigger is arranged to work in the slot 29, and the notched portions 36 of the plates of the trigger are arranged 120 to extend into the slot 28 of the standard 27, whereby the trigger is disposed in such relation to the standard that it may be pivotally mounted thereon by means of the transverse pin 40, the latter passing through suitable 125 apertures provided in the plates of the trigger 31 and in the sides of the slotted standard 27. The parallel plates of the pivoted trigger also carry or support the pins 41 and 130

42, the former of which is arranged in practically the same horizontal plane as the pivot-pin 40, so as to slidably support a setting-piece 52 for the sear-actuator, while the last-named pin 42 is adapted to retain in its place the spring 50, which actuates both the trigger and the sear-actuator, as will presently appear.

The sear-actuator for the trigger 31 is shown in detail by Fig. 7 and in its operative positions by Figs. 1, 2, and 3. This actuator is adapted to be mounted upon or carried directly by the pivoted trigger, and it is arranged to have active engagement with the 5 sear-tails 21 22 of the right and left hand gun-locks to be disposed in the path of the setting-piece 52 and to be held normally in one of its two active positions—i. e., in its forward active position—by the energy of the spring 20 50. It should be understood that the actuator has two active positions, in the forward one of which it is held by the spring 50, while in its rear active position it is held by the sear-tail of the right-hand lock. The actuator is indicated in its entirety by the numeral 43, and it is arranged between the parallel plates 33 34 of the trigger, the lower end of said actuator being pivoted near its lower extremity directly to the plates by means of 25 a pin 44. The upper free end of the actuator is arranged to extend above the top edges of the parallel plates forming a part of the trigger 31, and the upper front corner of the sear-actuator is notched to form a lip 45 and 30 a shoulder 46. In the style of gun under description the actuator 43 may have the extreme top face thereof curved at 47; but this is not essential, and, in fact, the top face of the actuator may slope down from the top of 35 the shoulder, as shown by Fig. 27. Furthermore, the actuator is provided on its front edge with a lip 48, adapted to serve as a seat for the rear end of the spring 50, the latter being bent to the curved form shown more 40 clearly by Figs. 1 and 10 and arranged to extend into the slot 35, which is formed by the parallel plates of the trigger. One end of this spring 50 bears directly upon the top face of the trigger-plate. The bent rear end of 45 the spring is snugly received in a recess or seat which is formed by the lip 48 of the sear-actuator, and a curved portion of the spring at a point intermediate of its length is arranged to press upwardly against the under side of the pressure-pin 42, which spans the 50 space or slot 35 of the trigger, whereby the single spring 50 exerts pressure against the trigger through the actuator and the actuator-pin 44, so as to hold the same normally in 55 a position to actuate the locks upon being pulled, and the same spring presses downwardly upon a seat of the sear-actuator in a manner to throw the upper unconfined end of said sear-actuator normally in a forward direction. The sear-actuator is, furthermore, 60 provided on that side or face thereof which is

opposed to the left-hand gun-lock with an off-standing lug 51, the same being disposed in rear of the lip 45 and the shoulder 46 and adapted to occupy a position wherein it will 70 engage with the sear-tail 22 of the left-hand gun-lock when the sear-actuator is permitted after the discharge of the first or right-hand barrel to be moved forwardly by the energy of the spring 50 into a position for engagement with said sear-tail 22 of said left-hand gun-lock.

The setting-piece 52, heretofore referred to, is slidably mounted on and between the parallel plates of the trigger. The setting-piece 80 is provided with a longitudinal slot 53, arranged to receive the pin 41 and the trigger-pivot 40, as clearly shown by Fig. 1, the length of this slot 53 being sufficient to allow the setting-piece to have the desired endwise 85 movement. The front end of the setting-piece is extended toward the cocking-lever 8, so as to terminate just in rear of the latter, while the rear end of the setting-piece terminates just in front of the sear-actuator 43, all 90 as clearly shown by Fig. 1, whereby the setting-piece is limited to a backward-and-forward reciprocating movement on the trigger, and it is adapted to be thrust rearwardly by the action of the cocking-lever 8 in order to 95 force the actuator 43 back to its rearward position for engagement with the sear-tail 21 of the right-hand gun-lock.

When the gun is opened for loading, the cocking-lever 8 is actuated, so as to force the two hammers of the right and left hand locks backwardly into engagement with the sears 18, thus cocking both of the locks, and simultaneously with this action of the parts the setting-piece 52 is forced backwardly by the 100 impingement of the cocking-lever 8 against its front end, thereby enabling the setting-piece to force the sear-actuator rearwardly against the pressure of the spring 50. This rearward movement of the sear-actuator 105 draws the lug 51 thereof away from engagement with the sear-tail 22 of the left-hand lock and brings the upper notched end of said sear-actuator in position to receive the sear-tail 21 of the right-hand lock, so that the 110 lower edge of the sear-tail will rest upon the lip 45, while the straight rear face 23 of said sear-tail rests against the shoulder 46 of the actuator. The parts thus assume the position shown by Fig. 1, which represents the 115 trigger mechanism in condition to actuate the sear for the lock of the right-hand barrel, and when the trigger is pulled the sear-tail 21 is raised to the position shown by Fig. 3, thereby releasing the hammer 13 from the sear 18 of the right-hand lock and allowing the spring 120 15 to forcibly impel the hammer against the firing-pin, so as to discharge the cartridge in the right-hand barrel. After having pulled the trigger the first time in order to discharge 125 the right-hand barrel and when the trigger is 130 released from the finger-pressure the spring 50

returns said trigger to its first position, and as soon as the sear-actuator has its notched end disengaged from the sear-tail 21 said sear-actuator is urged by the spring 50 into the position shown by Fig. 3. A second pull on the trigger will lift it and the sear-actuator against the tension of the spring 50, and the lug 51 of said sear-actuator will raise the sear-tail 22 and the sear of the left-hand lock, so as to permit the mainspring to throw the hammer against the firing-pin in a manner to discharge the cartridge in the left-hand barrel. Experience has shown that although this construction as described will work perfectly when tried by snapping the locks when the gun is unloaded, yet when it is tried with cartridges in the two barrels both the latter are frequently discharged by one pull on the trigger. The reason for this is probably as follows: When the trigger is pulled the first time and the cartridge in one barrel is discharged, the recoil of the gun caused by the shot drives the grip of the gun back through the hand to some extent, often sufficient to release the trigger, so that the sear-actuator flies forward into the position to discharge the cartridge in the second barrel. In the meantime the hand will have acquired the motion of the gun-stock, and when the stock is arrested by the resistance of the shoulder the hand will still keep up the motion and the trigger is pulled for the second time, and in consequence the cartridge in the second barrel is discharged. All this occurs so quickly that the shooter is not conscious of the release of the trigger or of the second pull and cannot perceive any interval between the shots and feels only one recoil. To overcome this difficulty, I employ the recoil-actuated locking-detent 54, which is mounted upon a stationary part of the gun, so as to occupy an operative relation to the trigger and is held normally free from engagement with the latter; but when the trigger is pulled the first time and is raised in order to make the right-hand lock discharge the cartridge in the first barrel this detent comes or is brought into locking engagement with the undercut edges 39 of the lugs 38 on said trigger in consequence of the recoil caused by the first shot. This locking-detent is shown in detail by Fig. 8 and in its normal position by Fig. 1, said detent having its lower end fitted loosely between the lugs 38 on the trigger-plate. A pivot-pin 55 passes through these lugs and through the lower portion of the detent 54, and with the lower end of this pivoted detent is engaged a spring 56, the same being secured by a screw 57 to the trigger-plate, as shown by Fig. 1. The spring is comparatively light, and its energy is just sufficient to normally hold the locking-detent in a stationary upright position and quite close to the rear edge of the plates 33 34 and the lugs 38 of the trigger. The locking-detent is furthermore provided on its front face with a cut-away portion forming a tooth 58, which occu-

pies such a relation to the trigger that it is adapted to engage with the undercut edges 39 of the lugs 38 on said trigger when the latter is in a partly-raised position and too high to allow the sear-actuator 43 to slip off the sear-tail 21 of the right-hand lock. Now when the trigger is pulled and the cartridge in the right-hand barrel is discharged the recoil drives the gun back through the right hand and the trigger is released, as heretofore explained; but as the detent 54 is quite heavy and as the spring 56 is weak the trigger will run or be impelled backwardly against the detent before the latter has acquired the motion of the rest of the gun due to the recoil, and consequently the tooth 58 will enter the notch of the trigger and have interlocking engagement with the lugs 38 thereof, thereby preventing the trigger from returning far enough for the sear-actuator to escape from the sear-tail of the right lock, and thereby attain a position suitable to discharge the cartridge in the left-hand barrel immediately after the discharge of the cartridge in the right-hand barrel. The undercut edges 39 of the lugs on the trigger are adapted to engage with a beveled top face of the tooth 58 on the locking-detent, so that the trigger will retain said detent in its forward position, and hence said trigger will remain safely held up by this engagement with the tooth on the pivoted detent, these parts being so proportioned that the trigger will be held so high that the sear-actuator will not shift until the gun comes to a period of rest, and the hand of the shooter, still continuing the motion occasioned by the recoil, again presses the trigger without the shooter ever knowing that he has let go the trigger. As soon as the shooter presses on the trigger, however slightly, and the trigger is moved so as to discharge the lugs 38 from the tooth 58 of the locking-detent the latter is at once brought back to its normal position by the spring 56, thus disengaging the locking-detent from the trigger. When the shooter now intentionally releases the trigger, the latter returns to its normal position by the spring 50 acting on the stud and on the rear portion of the trigger through the sear-actuator and its pin 44, and the sear-actuator is moved by the same spring, so as to bring the lug 51 into position for engagement with the sear-tail of the left-hand barrel, and hence a second intentional pull of the trigger duly discharges the cartridge in the second barrel.

It is to be understood from the foregoing description that the function of the detent 54 is to prevent the trigger from returning far enough toward its normal position to allow the sear-actuator to change its position while the gun is recoiling. It is essential that the detent 54 shall be tolerably heavy in order that it may have sufficient inertia to overcome the force of the spring 56, the latter serving to hold said detent in its rearmost position just clear of the trigger, and also that the

spring 56 shall be only sufficiently strong to return the detent to its normal position promptly.

To insure the certain action of the recoil-detent, it may be advisable to so arrange the parts as to utilize the last part of the movement of the trigger when pulled as the medium to positively force the detent under the rear of the trigger, so as to be ready to hold the trigger up in case of an involuntary release caused by the recoil already explained. In Figs. 13 and 14 I have shown the positive connection between the trigger and the detent as adapted for a "Baker" gun.

In Figs. 13 and 14 it will be seen that a narrow finger 154 is put on the lower rear part of the trigger and a narrow slot is cut in the trigger-plate back from the wide trigger-slot to allow it to pass through between the lugs 30 on the trigger-plate. The rear extremity of this finger 154 is turned up slightly in order that when the trigger is pulled back as far as it will go it may engage the rear lower corner of the detent and by forcing this corner up throw the upper part of the detent forward and the tooth 58 into locking engagement with the trigger. The forward end of the spring 56, which passes under the detent, must be slotted or perforated to allow the finger 154 to pass through to engage the detent. Now if the trigger is released unintentionally while the gun is recoiling the action of the recoil, as explained before, will be to keep the detent in engagement with the trigger, so that the trigger cannot move far enough to free the sear-actuator from engagement with the sear. Consequently the actuator cannot shift into engagement with the left sear. The unintentional pull is then given as the gun ceases its recoil, and then the trigger is intentionally released. As the finger 154 commences to fall the tooth 58 will be moved back from the trigger by the spring 56 and will be out of the way of the shoulders 39 as the trigger returns to its normal position.

The detent instead of being actuated directly by a spur on the trigger may be actuated by any other convenient way of communicating the motion of the trigger to the detent.

Of course it will be understood that the non-essential features and details of the construction may be varied more or less from the form described without departing from my invention.

Having thus described my invention, what I claim as new is—

1. In a firearm, the combination with gun-locks, of a trigger provided with means for successively actuating the gun-locks and having a locking-shoulder, a detent mounted in operative relation to the trigger and arranged to have interlocking engagement with said locking-shoulder and having a squared lower end, and a detent-spring pressing upwardly

against said squared lower end to normally hold said detent free from the trigger, substantially as described.

2. In a firearm, the combination with gun-locks, of a trigger provided with a downwardly-facing locking-shoulder and having means for successively actuating said gun-locks, a detent mounted on a stationary pivot adjacent to the trigger and having an upwardly-facing shoulder arranged to interlock with the locking-shoulder and having a squared lower end, and a detent-spring pressing upwardly against said squared lower end to normally hold said detent free from the trigger, substantially as described.

3. In a firearm, the combination with an action mechanism, and locks provided with sears, of a single trigger, a sear-actuator mounted on the trigger to engage successively with the sears, means controlled by the action mechanism to set the sear-actuator in position to fire the first barrel, a detent on a stationary pivot adapted to have interlocking relation with the trigger to check its return motion in the interval between the first and second shots, said detent having a squared lower end, and a spring pressing upwardly against said squared lower end.

4. In a firearm, the combination with gun-locks having sears, of a single trigger, a sear-actuator pivoted to said trigger, and a single spring arranged to hold the trigger in operative relation and to urge the sear-actuator to one of its operative positions, substantially as described.

5. In a firearm, the combination with gun-locks, of a trigger provided with means for successively actuating the gun-locks and having a locking-shoulder, a detent mounted in operative relation to said shoulder and adapted to engage therewith upon the discharge of the gun to prevent said trigger from returning immediately to its normal position, and means carried by said trigger for positively forcing said detent into engagement with said locking-shoulder.

6. In a firearm, the combination with gun-locks, of a trigger provided with means for successively actuating the gun-locks and having a locking-shoulder, a detent pivoted at its lower end mounted at the rear of the trigger and adapted to engage with said locking-shoulder to hold the trigger raised, and a spur carried by the trigger adapted to press against the lower portion of said detent when the trigger is pulled so as to positively turn said detent about its pivot and cause it to engage with said locking-shoulder, substantially as described.

In witness whereof I have hereunto set my hand in the presence of two witnesses.

JAMES JOHN HEWSON.
